(57) **CLAIM**

The ornamental design for a front cowl for a vehicle, as shown and described.

DESCRIPTION

FIG. 1 is a front perspective view of the front cowl for a vehicle in an environment of use;

FIG. 2 is a front perspective view of the front cowl for a vehicle;

FIG. 3 is a front elevation view thereof;

FIG. 4 is a rear elevation view thereof;

FIG. 5 is a side elevation view thereof;

FIG. 6 is an opposite side elevation view thereof;

FIG. 7 is a top plan view thereof; and,

FIG. 8 is a bottom plan view thereof.

The broken line showing of parts of the drawings is included for the purpose of illustrating background environment and forms no part of the claimed design. The dash-dot broken lines are boundary lines which define the edge of the claimed design and form no part of the claimed design.

1 Claim, 7 Drawing Sheets
